SOLE FOR FOOTWEAR

Roger Tornero, Naugatuck, Conn., assignor to Uniroyal, Inc.

Filed Mar. 8, 1974, Ser. No. 449,806

Term of patent 14 years

Int. Cl. D2—04

U.S. Cl. D2—320

FIG. 1 is a bottom plan view of a sole for footwear embodying my new design;

FIG. 2 is a side elevational view thereof;

FIG. 3 is an elevational view of the other side; and

FIG. 4 is a sectional view of the FIG. 1 sole taken along line 4-4 of FIG. 1.

I claim:

The ornamental design for a sole for footwear, substantially as shown.
